UNITED STATES PATENT OFFICE

2,634,436

WATERCRAFT

Lawrence Plaziak, Rice, Minn., assignor of one-fifth to John Plaziak, one-fifth to Felix Plaziak, one-fifth to Ben Plaziak and one-fifth to Frank Plaziak, all of Rice, Minn.

Application June 10, 1948, Serial No. 32,072

3 Claims. (Cl. 9—6)

1

This invention relates generally to boats and more particularly to a boat constructed largely from a single sheet of metal and having novel prow and stern shapes.

A primary object of this invention is to provide a boat of unitary construction having a stern in which the bottom of the boat is extended beyond a substantially vertical end plate, the extending portion being recessed adjacent a longitudinal center line of the boat to receive an intermediate portion of an outboard motor, the provision of these extending portions resulting in increased speed, and greater stability of the boat.

Another object of this invention, ancillary to the preceding object, is to provide the extending portions at the stern of a boat, disposed rearwardly of the outboard motor mounted thereon, so that the prow of the boat is prevented from rising out of the water any considerable distance, even at greater speeds.

Still another object of this invention, is to provide an improved stern construction for a boat which will enable very slow speeds to be attained, even with the use of relatively powerful motors, the braking action of this stern construction being accentuated at slow speeds.

Still another object of this invention is to provide a boat construction in which the prow is formed from a single sheet of material cut with a pair of slots having each a straight edge on the side adjacent the center line of the boat and a curved edge on the side of the slot remote from said center line, the said edges being seamed and the sheet being bent along said center line.

And a last object to be mentioned specifically is to provide a boat which is relatively inexpensive and practicable to manufacture, which is safe, simple and convenient to use, which has a dual advantage of facilitating the attaining of both very high and very low speeds of propulsion, and which will give generally efficient and durable service.

With these objects definitely in view, this invention resides in certain novel features of construction, combination and arrangement of elements and portions as will be hereinafter described in detail in the specification, particularly pointed out in the appended claims, and illustrated in the accompanying drawings which form a material part of this application, and in which:

Figure 1 is a top plan view of the assembled boat;

Figure 2 is a side elevational view of the boat;

Figure 3 is a plan view of a sheet of material

slotted and formed while flat and before being bent and seamed to comprise the boat;

Figure 4 is a longitudinal vertical sectional view of the boat;

Figure 5 is a three dimensional view of the stern portion of the boat; and

Figure 6 is a cross sectional view of the boat, the view being taken substantially on a transverse line mid-length of the boat.

Similar characters of reference designate similar or identical portions and elements throughout the specification and throughout the several views in the drawings.

Referring now to the drawing in detail, this boat is constructed largely from a sheet of suitable metal such as commercially supplied aluminum, first formed as indicated in Figure 3 with an elongated central portion 10 which becomes the bottom portions 12 of the boat when bent 10 slightly along a longitudinal center line, that is, at the keel 14 of the boat as indicated in Figure 6.

The lateral portions 16 in Figure 3 become substantially dead-rise sides 18 of the boat, and a pair of laterally disposed slots each having an outwardly disposed curved edge 20 and an inwardly disposed straight edge 22 are cut in the sheet material at one end so that on seaming the said edges, by curved plates 24 and rivets 26, a streamlined prow is achieved, it being understood that the sheet material will also be first formed 25 with a central slot having arcuate edges 28. The sheet will be bent along a longitudinal center line and the edges 28 will be seamed and reinforced by another plate 30. This plate 30 serves to join the corresponding substantially straight edge portions 32 between the slots and similar laterally disposed portions 32', to comprise an upper prow portion 34 in the assembled boat.

An outer prow reinforcing plate 35 may be secured in place by the same rivets as are used to fasten the plate 30 in place.

The lateral edges 36 of the tapered sheet of material are straight throughout the greater portions of their lengths but the angle or taper is increased near the larger end of the sheet, as at 38 in Figure 3. A deck plate 40 is secured to the portions 42 of these edges in the assembled boat.

Top rails 44 of channel form reinforce the upper edges of the sides of the boat, and sheer strakes 46 of any suitable form are secured to the sides of the boat. The stern includes a substantially vertical end plate 48 having attachment flanges 50 secured to the bottom and sides of the boat, and corner plates 52 having flanges 54 secured to the top of the plate 48 and to the top

of the adjacent portions of the sides of the boat.

The bottom and the sides of the boat are extended as at 54 and the extended portions have curved edges. A central recess 56 to receive an intermediate portion of an outboard motor, which is not illustrated, is provided adjacent the center line of the boat, the corresponding recess in the sheet material being indicated at 58 in Figure 3. The extending portions at 54 and the end plate 48 define a well at the stern of the boat. The vertical triangular plate braces 60 are secured to the rear side of the plate 48 and to the extensions 54, these plate braces functioning as such in supporting said extensions and end plate and also functioning to give better definition to those portions of the well at each side and at the stern of the boat, by dividing the well into conterminous compartments. Blocks 62, preferably constructed of wood, are secured centrally of the plate 48 for attachment thereto of an outboard motor. A complement of seats 64, illustrated as of channel form, may be rigidly secured to the sides of the boat and transversely thereof.

The operation of this invention will be clearly understood from the foregoing description of the mechanical details thereof, taken in connection with the above recitation of the objects sought to be achieved by this invention and the accompanying drawings. In recapitulation, it may be stated that an operator of the boat seated upon the rearmost seat 64 may drive the boat at high speeds without causing the raising of the prow portion of the boat any considerable distance out of the water. Conversely, when the speed of the motor is reduced to a minimum, the well formed at the rear of the end plate, at both sides of the outboard motor, acts as a very effective brake, the well filling nearly completely with water when the weight in the boat is concentrated near the stern thereof. It will be clear how the instant invention achieves all the objects recited above, all without sacrificing maneuverability.

Obviously many minor variations may be made in the exact construction and proportionment of the various elements of this invention without departure from the spirit and scope thereof. Accordingly, this invention should be limited only in accordance with a proper interpretation of the terminology used in the subjoined claims.

Having described the invention, what is claimed as new is:

1. A metal boat having a hull including sides and a bottom, an end plate closing the stern of said boat, said hull extending beyond the rear of said end plate and terminating at a distance from said end plate, the hull extension having a notch in the central portion thereof and terminating in curved edges, said notch terminating adjacent the center of the bottom of said end plate, spaced triangular braces mounted on said hull extension and engaging said end plates thereby dividing the hull extension into conterminous compartments and serving as guiding fins.

2. The combination of claim 1, wherein said hull is of one piece construction.

3. A substantially rectangular blank adapted to form the hull of a boat, one end of said blank being provided at the edge with spaced notches, one along the longitudinal center line of said plate and one spaced at each side of said center line, the edges defining the central notch being uniformly outwardly curved from the apex of the notch, the inner edges defining the spaced notches being straight and the outer edges being uniformly outwardly flared whereby upon bending of the plate along the longitudinal center line the notched edges on either side of the center line will be adjacent one another thereby forming the prow of the boat.

LAWRENCE PLAZIAK.
